UNITED STATES PATENT OFFICE.

MICHAEL M. MAHER, OF KITTANNING, PENNSYLVANIA, ASSIGNOR OF
TWO-THIRDS TO ROBERT BARNER AND J. C. WOODWARD, OF KIT-
TANNING, PENNSYLVANIA.

GLASS-MELTING FURNACE.

SPECIFICATION forming part of Letters Patent No. 757,666, dated April 19, 1904.

Application filed September 22, 1902. Serial No. 124,327. (No model.)

To all whom it may concern:

Be it known that I, MICHAEL M. MAHER, a citizen of the United States, residing at Kittanning, in the county of Armstrong and State 5 of Pennsylvania, have invented certain new and useful Improvements in Glass-Melting Furnaces, of which the following is a specification, reference being had therein to the accompanying drawings.

10 This invention relates to that class of glass-melting furnaces adapted to inclose portable pots in which glass for casting into plates or sheets is melted and refined; and the primary object is to provide for uniform circulation 15 of the heat throughout all portions of the furnace, and, further, to provide means for so directing and redirecting the ignited gases and products of combustion through the furnace and around the same that the efficiency there- 20 of is spent before escaping to the stack, thereby minimizing the fuel consumption and avoiding waste.

In the accompanying drawings, Figure 1 is a top plan view, partly in section, of a furnace constructed in accordance with my invention, the portion in section, save the stack, being on line 1 1 of Fig. 2. Fig. 2 is a vertical longitudinal sectional view of the same on line 2 2 of Fig. 1. Fig. 3 is an end elevation. Figs. 4 and 5 are vertical cross-sectional views taken on lines 4 4 and 5 5, respectively, of Fig. 1. Fig. 6 is a side elevation of a portion of the furnace.

In the preferred embodiment of the invention 35 the furnace is of double form, being constructed with two parallel ovens or chambers 2 and 3, separated by partition-wall 4. Each of these ovens is continuous from end to end, and removably positioned therein are the 40 glass-melting pots 5, of usual design. The outer open sides of the ovens are closed by vertically-sliding doors 6, which bear in the angular columns or ways 7, the latter being inclined slightly, as are also the outer edges of 45 end walls 8 and 9, whereby the doors are held

in place. The doors are raised and lowered by chains 10, adapted to detachably connect therewith, which at their upper ends are secured to and adapted to wind on horizontal shafts 11, journaled in suitable bearings 12 on 50 the furnace-crown. Each of the shafts may be rotated by chain gearing 13, depending to crank-wheel 14, sustained by the furnace end wall or by other suitable means. For operating any given door the chains 10 therefor 55 are connected thereto, the inactive chain simply winding and unwinding idly on shaft 11 as it rotates. The arrangement is preferably such that each door closes a passage-way for two of pots 5, being the usual practice in this 60 class of furnaces.

The position or station for each pot is central over a gas-burner 15 in chamber 16 beneath the furnace-floor, with the upwardly-radiating ducts 17 extending from said chamber and opening through the floor, forming a circle of flame-emitting orifices, and with the pot located within this circle it is completely enveloped by the burning gas and subjected to a direct and very intense heat, the 70 volume thereof being regulated by valve 18 in burner-pipe 15', extending inward from gas-manifold 19, located in longitudinal area-way 20, covered by grating 21.

At one end of the furnace is stack 22, and 75 at said end the upper portions of ovens 2 and 3 communicate through horizontal duct 23, opening centrally through the end wall of each oven at 23'. Opening centrally at 24 into the front ends of ovens 2 and 3 are vertical ducts 80 25 and 26, respectively, in end wall 8, said ducts communicating at their lower ends with transverse duct 27 in wall 8, from which extend the horizontal flues 29 longitudinally beneath the furnace-floor, which discharge into 85 the base of stack 22. There are preferably four of these flues, two beneath each oven.

At the front end of the furnace is fan or blower 30, of usual or any preferred design, having its intake-pipe 31 extending from stack 90

22 longitudinally over the furnace and discharging centrally into a transverse pipe 32, opening at its opposite ends into vertical ducts 25 and 26, said pipe on opposite sides of the blower being provided with dampers 32' and 32''. Beneath pipe 32 ducts 25 and 26 are provided, respectively, with dampers 25' 26'. The length of the furnace will be governed by the capacity desired. It may be constructed to receive any desired number of pots, preferably in multiples of two, in each oven. In operation the burners are lighted and adjusted to afford the heat requisite for each pot. The blower is then started, drawing its supply from stack 22, and, say, with dampers 32' and 26' closed and dampers 32'' and 25' open the blower will discharge across the upper end of duct 26 and through opening 24 into the upper portion of oven 3, thereby creating a draft through the latter toward the rear end which discharges through duct 23 into the rear end of oven 2 and through the latter forward or toward its front end in direction reverse to that followed in oven 3. The impetus thus given the air and ignited gases in passing through oven 3 is sufficient to effect a reversal of the current in oven 2 but this tendency is accelerated by the stack-draft drawing through floor-flues 29 and downward through the then open flue 25, leading from the front end of oven 2. By closing dampers 32'' and 25' and opening dampers 32' and 26' the operation is reversed, the blower then discharging into oven 2 and the draft in oven 3 being toward the front and emerging through duct 26 and the floor-flues to the stack. Thus a practically uniform temperature may be maintained in each oven, the described reversal of the valves being made frequently and before the heat of either oven far exceeds the other. The heated air and products of combustion are thus fully utilized and their efficiency spent before discharging into the stack. Passage thereof through floor-flues 29 heats the floor and maintains the same heated. As the blower draws its supply from near the base of the stack through pipe 31, said supply consists largely of heated air and products of combustion which discharge into the stack from flues 29, so that the current discharging from the blower is heated, and hence far more effective than though it were cold.

While the invention as here embodied involves the employment of two ovens, with means for reversing the current in either oven, I do not thus restrict myself, as in its broader aspect the invention contemplates maintaining a draft from end to end of a glass-melting furnace, with means for reversing the same, without regard to the number of ovens employed, and hence the structural arrange-

ment whereby this result is attained is immaterial.

Having thus fully described my invention, 65 what I claim as new, and desire to secure by Letters Patent, is—

1. An improved glass-melting furnace comprising two communicating chambers, valved stack and valved blower connections for each chamber whereby draft may be maintained alternately in reverse directions through the chambers, and heating means independent of the stack and blower connections.

2. An improved glass-melting furnace comprising two chambers in communication at one point only, valved stack and valved blower connections for the non-communicating portion of each chamber whereby draft may be maintained alternately in reverse direction through the chambers, and heating means independent of the stack and blower connections. 75
80

3. An improved glass-melting furnace comprising two chambers arranged side by side and in communication at one end only, valved stack and valved blower connections for the non-communicating end of each chamber whereby draft may be maintained alternately in reverse directions through the chambers, and heating means independent of the stack and blower connections. 85 90

4. An improved glass-melting furnace comprising two chambers communicating at one point only, a single stack and a single blower each having valved connection with the non-communicating portion of each chamber whereby draft may be maintained alternately in reverse directions through the chambers, and heating means independent of the stack and blower connections. 95

5. In a glass-melting furnace, a chamber, valved stack connections for opposite portions of the chamber whereby draft may be maintained therethrough alternately in reverse directions, heating means at the bottom of the chamber, and pots adapted to be removably positioned in the chamber.

6. In a glass-melting furnace, two chambers in communication at one end only, a valved stack connection for the opposite end of each chamber whereby draft may be maintained through the chambers alternately in reverse directions, heating means at the bottom of each chamber, and pots adapted to be removably positioned in the chambers. 115

7. An improved glass-melting furnace divided by a central wall into two communicating chambers each provided with an outlet, means for creating a draft from either chamber into the other, pots removably positioned in the chambers, and heating means. 120

8. An improved glass-melting furnace comprising a chamber, a stack, flues beneath the chamber communicating with different por-

tions thereof and with the stack, means for causing the chamber to discharge into the flues through either of said points of communication, and heating means.

5 9. An improved glass-melting furnace comprising two chambers in communication at one end, flues beneath the chamber-floors having valved communication therewith, a stack with which said flues communicate, means for creating a draft in either chamber which flows

into and through the other chamber and from thence through the floor-flues into the stack, and heating means.

In testimony whereof I affix my signature in presence of two witnesses.

MICHAEL M. MAHER.
